ALARM DEVICE

Filed Oct. 27, 1950

UNITED STATES PATENT OFFICE

2,630,095

ALARM DEVICE

Alvia G. Thorpe, Glendale, Calif., and John A. Padjen, Salt Lake City, Utah

Application October 27, 1950, Serial No. 192,474

6 Claims. (Cl. 116—86)

1

This invention relates generally to the art of signals, and more particularly to devices for signalling unauthorized entry of premises as a warning to occupants thereof.

An object of this invention is to provide an alarm device particularly adapted, although not necessarily, for application to a closure such as the door of a private room or building in a manner to be automatically activated in response to opening movement of the closure, so as to warn any occupants of the room of any unauthorized attempt of entry to the room.

Another object of this invention is to provide an alarm device of the above described character which is a self-contained unit of comparably simple and inexpensive construction, sufficiently compact and light in weight to enable it to be conveniently carried in the luggage of travelers, and adapted to be instantly set and quickly applied to and detached from any door of a room, to automatically function in response to opening movement of the door to sound an alarm sufficiently loud and compelling to awaken sleepers and thus protect any sleeping occupants of the room against unauthorized entry.

With these and other objects in view, this invention resides in the combinations, arrangements and functional relationships of elements as set forth in the following specification and particularly pointed out in the appended claims.

In the accompanying drawings,

Figure 1 is a view in front elevation, of one form of alarm device embodying this invention, with the device in set position and the gong of the device removed to expose its mechanism;

Figure 2 is a transverse sectional view taken on the line 2—2 of Figure 1 and showing the device in set position and applied to a closed door;

Figure 3 is a view similar to Figure 2 and illustrating the tripped position of the device to sound the alarm in response to any opening movement of the door;

Figure 4 is a fragmentary view similar to Figure 2 and illustrating an initial setting position of the device preparatory to operatively relating the device to the jamb of the door in response to closing of the door with the device attached thereto;

Figure 5 is a fragmentary sectional view taken on the line 5—5 of Figure 2 and illustrating a gear train embodied in the device; and

Figure 6 is a fragmentary detail sectional view taken on the line 6—6 of Figure 2 and illustrating a friction clutch embodied in the device.

Referring specifically to the drawings, this invention, for the purpose of illustration, is shown

2

associated with a manually operable type of bell comprising a shallow, cup-shaped support or body 10 in which is secured a frame 11 having fixed thereto co-axially of the body 10, a threaded stud 12 on which is screwed a threaded sleeve 13 fixed co-axially in the inner side of a gong 14, which, in its applied position, shown in Figure 2, closes the open side of the body.

By means of a driving pinion gear 15, a rotary 10 clapper 16 is freely mounted on the stud 12 and is confined between the frame 11 and the free end of the sleeve 13 against axial displacement. The clapper 16 is provided at its ends with loosely mounted disk-shaped weights 17 constituting 15 hammers and adapted to successively strike an internal, fixed projection 18 in the gong 14 so as to vibrate the latter in response to rotation of the clapper.

A manually operable actuator 19 in the form 20 of a curved arm is pivotally mounted in the body 10 for movement about a fixed axis 20 and projects from the body for manual actuation in co-action with a fixed ear 21, on the body, from the position shown in broken lines in Figure 1 to the position shown in full lines in this figure, and against the action of a loaded coil spring 22. A portion of the peripheral surface of the actuator 19 is formed to provide a segmental gear 23 constantly meshing with a pinion gear 24 (Figure 5) fixed to a relatively large gear 25, the gears 24 and 25 being mounted for rotation as a unit on a fixed stub shaft 26 projecting from the body 10.

The gear 25 constantly meshes with a pinion gear 27 rotatably mounted on a second fixed stub shaft 28 projecting from the body 10. Also rotatably mounted on the shaft 28 is a relatively large gear 29 which constantly meshes with the driving pinion gear 15. The gear 29 is operatively connected to the gear 27 for rotation by the latter in one direction only, by a pawl 30 pivotally mounted at 31 on the gear 29 and yieldingly urged into engagement with the teeth of the gear 27 by a wire spring 32 fixed at one end to the gear 29 and bearing at its free end against the pawl.

The direction in which the gear 29 will be driven by the gear 27 is such that upon movement of the actuator 19 from its broken line position in Figure 1 to the full line position in this figure to load the spring 22, will drive the gears 24, 25 and 27 idly from the segmental gear 23, as the teeth of the gear 27 will click freely past the pawl 30 without transmitting movement to the gear 29, with the result that the clapper 16 will remain at rest.

However, upon movement of the actuator 19

from its full line position to its broken line position in Figure 1 under the action of the loaded spring 22, the gear 29 will be positively driven by the gear 27 through the pawl 30, so as to rotate the clapper 16 at high speed for coaction of the clapper weights 17 with the projection 18 in vibrating the gong to sound an alarm.

For the purpose of this invention, one end of the clapper arm 35 is provided with a keeper in the form of a radially projecting latching lug 36 with which a detent 37 on a latching member 38 is adapted to have latching engagement to prevent rotation of the clapper 16 under the action of the spring 22. The latching member 38 and a tripping member 39 are co-axially mounted on a sleeve 40 (Figure 6) which co-acts with a spring washer 41 to yieldingly press the members together so that their confronting surfaces form a friction clutch 42 between the members.

The sleeve 40 is freely mounted on a fixed stub shaft 45 projecting from a side of the frame 11, so that the members 38 and 39 may either pivot as a unit on the shaft 45 under the action of the friction clutch 42, or pivot independently of each other upon overcoming the friction of the clutch.

A coil spring 50 is secured at one end to a stop pin 51 on the tripping member 39 and is connected at its other end to the frame 11 so as to normally urge the member to its tripping position shown in Figure 3. The members 38 and 39 project from a side of the body 10 through a slot 52 in the latter, with the member 38 having a finger piece 53, and the member 39 an arm 54 of sufficient length to overlie the jamb J of a door D when the body 10 is applied to the door adjacent to its free vertical edge as shown in the drawings. A plurality of suction cups 55 project from the back of the body 10 at circumferentially spaced locations and provide a simple and convenient means for detachably securing the device to the door for operation of the device which is as follows:

With the members 38 and 39 occupying their released position shown in Figure 3, under the action of the spring 50, and wherein the pin 51 rests against the back of the body 10 to definitely limit such position, the detent 37 will be clear of the latching lug 36 on the clapper 16 so that the latter will be free to rotate.

The device may now be set for use, upon manually turning the latching member 38 on the sleeve 40 in the direction of the arrow in Figure 4, and independently of the tripping member 39, by overcoming the friction of the clutch 42 until the detent 37 has been moved into the path of movement of the lug 36 as shown in this figure. As the tripping member 39 is occupying its extreme tripping position shown in Figure 4, under the action of the spring 50, the latching member 38 will remain in its latching position shown in this figure, so as to prevent rotation of the clapper 16.

The manually operable actuator 18 is now moved from its broken line position to its full line position in Figure 1, so as to load the spring 22 and complete the setting of the device which may now be applied by the suction cups 55 to the closed door D of the room to be protected. As the suction cups are pressed against the door, the arm 54 of the tripping member 39 strikes the jamb J and is thus caused to turn on the sleeve 40 relative to the latching member 38 in the direction of the arrow in Figure 2, to the position shown in this figure.

Should any attempt be made to gain entry by opening the door, the initial opening movement

of the door as illustrated in Figure 3, will render the spring 50 free to reversely move the tripping member 39 on the sleeve 40. As the clutch 42 provides sufficient friction for the latching member 38 to move with the tripping member 39, the detent 37 of the latching member will be freed from the lug 36 of the clapper 16 so that the latter will be rapidly rotated under the action of the spring 22 so as to co-act with the gong projection 18 in sounding an alarm.

From the foregoing description it will be manifest that the alarm device embodying this invention may be conveniently carried about in traveler's luggage so as to be available when needed, and can be instantly set and applied to any door to provide a positive and certain means for sounding an alarm should any opening movement of such door be effected, thus providing much needed protection against unauthorized entry of premises.

What is claimed is:

1. An alarm device comprising: a support adapted to be mounted on a door; a signal mounted on said support and including an element normally urged to activate the signal; a latching member releasably retaining said element against activation of the signal; a tripping member engageable with the structure in which the door is mounted; means movably mounting said latching and tripping members on said support; means urging said tripping member in one direction for movement to a tripping position in response to opening movement of the door from closed position; and friction clutch operatively connecting said latching and tripping members for movement as a unit when the tripping member moves to its tripping position, so as to free the latching member from said signal element for activation of the signal thereby, yet render the latching member independently movable to its latching position with respect to said signal element for setting the alarm.

2. An alarm device comprising: a support adapted to be mounted on a door; a signal mounted on said support and including an element normally urged to activate the signal; a latching member for releasably retaining said element against activation of the signal; a tripping member engageable with the structure in which the door is mounted; means mounting said latching and tripping members for pivotal movement about a common axis on said support; means urging said tripping member in one direction for movement to a tripping position in response to opening movement of the door from closed position; and means frictionally engaging said latching and tripping members for movement as a unit when the tripping member moves to its tripping position, so as to free the latching member from said signal element for actuation of the signal thereby yet render the members independently movable for adjustment of the latching member to its latching position with respect to said signal element to set the alarm.

3. An alarm device comprising: a support adapted to be mounted on a door; a signal mounted on said support and including an element normally urged to activate the signal; a latching member releasably retaining said element against activation of the signal; a tripping member engageable with the structure in which the door is mounted; a sleeve on which said latching and tripping members are rotatably mounted; a stud carried by the support on which said sleeve is mounted; a spring connecting said support and

tripping member to urge the latter to a tripping position; and spring means mounted on said sleeve and co-acting therewith to urge the latching and tripping members into frictional engagement with sufficient force for movement of the members as a unit when the tripping member moves to its tripping position in response to opening movement of the door from its closed position, so as to free the latching member from said signal element for activation of the signal thereby; said frictional engagement of the members being insufficient to resist manual adjustment of the members independently of each other so as to enable the alarm to be set by manually moving the latching member to its latching position with respect to the signal element while the tripping member is held against movement with the latching member.

4. An alarm device comprising: a support adapted to be mounted on a door; a gong mounted on said support; a rotary clapper urged to rotate in one direction to repeatedly strike said gong; a latching lever for preventing rotation of said clapper; a tripping lever having an arm engageable with the structure in which the door is mounted; means pivotally mounting said levers about a common axis on said support; means co-acting with the tripping lever to urge same in one direction for movement to a tripping position; and means yieldingly pressing said levers into engagement to provide a friction clutch between the levers by which same are caused to move as a unit when the tripping lever moves to its tripping position in response to opening movement of the door from its closed position, so as to free the latching lever from the clapper for sounding of the alarm; said clutch enabling said levers to be independently adjusted manually for movement of the latching lever to its latching position.

5. An alarm device comprising: an audible signal adapted to be mounted on a closure; means for releasably retaining said signal against

- activation; trip means engageable with the structure in which the closure is mounted; means operable to move said trip means to a tripping position upon opening movement of the closure from its closed position; means operatively connecting said retaining and trip means for movement as a unit when the trip means moves to its tripping position, so as to free said retaining means from said signal and enable the latter to sound the alarm; said last means enabling the said retaining means to be moved independently of the trip means for setting of the alarm by adjustment of the retaining means to prevent activation of the signal.
- 15 6. An alarm device comprising: an audible signal adapted to be mounted on a closure; means for releasably retaining said signal against activation; trip means engageable with the structure in which the closure is mounted; means operable to move said trip means to a tripping position upon opening movement of the closure from its closed position; a friction clutch operatively connecting said retaining and trip means for movement as a unit when the trip means moves to its tripping position, so as to free said retaining means from said signal and enable the latter to sound the alarm; said friction clutch enabling the retaining means to be moved independently of the trip means for setting of the alarm by adjustment of the retaining means to prevent activation of the signal.
